UNITED STATES PATENT OFFICE

ROBERT S. RODIE, OF KINGSTON, NEW YORK

AUTOMATIC FUEL CONTROL FOR BOILERS

Application filed October 29, 1931. Serial No. 571,844.

This invention relates to improvements in heating apparatus and, with reference to some of its features, it relates more particularly to automatic fuel control for boilers for supplying hot water, vapor or steam for heating purposes. While the improved apparatus is especially well designed and adapted for heating homes, buildings and so forth, it is serviceable also for producing steam for motive power.

It is a general object of the invention to provide a heating apparatus of the class mentioned wherein an improved automatic fuel feed is provided, well adapted for the automatic control of fuel coal to the combustion chamber of the furnace. The improved fuel control is advantageously arranged for the automatic feeding of the coal to the furnace without requiring the services of an attendant, except for servicing and supplying the fuel at relatively long periods. The improved apparatus is arranged so as not to require the services of an attendant, having once been supplied with fuel, for two to six days or even for a longer period, the fuel feed and control during such period being entirely automatic. While the improved apparatus is well adapted for utilizing various sizes and grades of coal or coke, it is especially well adapted for using the small sizes, such as buckwheat coal, and it is also effective in using fine powdered coal, such as culm.

It is a further and important object of the invention to provide an improved automatic fuel feed control for heating apparatus of the class mentioned wherein the fuel coal is caused to flow automatically in opposite directions to the combustion chamber so as to constantly maintain a ribbon of fire beneath the boiler.

A further object of the invention is to provide fuel spreaders for automatic fuel feed, whereby the fuel level in the combustion chamber is automatically maintained at the correct position with reference to the grate and to the crown plate or heating surface of the boiler.

Another object of the invention is to provide improved fuel spreaders or controls for the automatic fuel feed which may be adjust-

ed to vary the level of the fuel in the combustion chamber.

Still another object of the invention is to provide an improved heating apparatus wherein the boiler can readily be removed from its mounting in the furnace for repairs and so forth, while another similar boiler may be substituted during the time repairs are being made upon the first.

According to another feature of the invention, an improved automatic gravity fuel feed is provided whereby the fuel is caused to flow in opposed streams or courses and meeting each other in the combustion chamber. By means of this arrangement the furnace is well adapted to burn the small sizes or a mixture of different sizes of anthracite or bituminous coal, coke, and similar fuels. Any inferior grades of coal may thus be used, greatly reducing the expense of running the heating apparatus while at the same time providing for large steaming capacity and satisfactory automatic fuel control.

A further object of the invention is to provide a compact comparatively inexpensive boiler and heating apparatus of simple structure and large steaming capacity with great strength to ensure safety against explosion.

Other objects of the invention will be, in part, pointed out in the following detailed description of an illustrative but preferred embodiment of the invention and will be, in part, obvious in connection therewith.

The invention accordingly comprises the features of construction, combinations of elements, and arrangement of parts, which will be exemplified in the construction hereinafter set forth and the scope of the application of which will be indicated in the claims.

For a more complete understanding of the nature and objects of the invention, reference is had to the accompanying detailed description of the illustrative embodiment and to the drawings, in which

Fig. 1 is a longitudinal central vertical section of a heating apparatus embodying the invention, the disclosure being partially diagrammatic to facilitate the illustration.

Fig. 2 is a vertical transverse section sub-

stantially on the line 2—2 of Fig. 1, looking in the direction of the arrows.

Fig. 3 is a section on reduced scale substantially on the line 3—3 of Fig. 1, looking 5 in the direction of the arrows, and

Fig. 4 is a fragmentary side elevation of one of the fuel spreaders or wing plates.

Referring to the drawings for a detailed 10 description of the illustrative embodiment of the invention, a boiler 5 is provided which generally may be of a known type of construction. A boiler of the fire tube type is shown having a cylindrical shell of fire box steel or similar metal with tube heads 6 in 15 which the fire tubes 7 are fitted and expanded so as to make tight joints. A connection 8 for the outwardly flowing steam or hot water is connected with the boiler communicating with the interior space thereof while a 20 pipe or connection 9 is provided for the return flow.

The boiler proper is mounted in a supporting structure embodying the furnace. Insofar as this mounting structure is concerned, it may be generally of known construction embodying a cast iron casing lined with fire brick or similar non-conducting refractory material and having side walls 10 and end walls 11 providing supports in which 25 the boiler is set. The grate bars 12 are mounted in the furnace walls extending longitudinally of the boiler and a door 13 in the front wall communicates with the combustion chamber 14. The grate bars 12 may be of any 30 well known preferred construction, being shown as of the rotary type, which may be operated in any desired manner through an operating connection 15. For operating the grate bars, it is preferred that an electric motor (not shown) be used and automatically controlled to shake the grate bars at desired 35 intervals so as to relieve the fire bed of the accumulated ash. An ash compartment is provided beneath the grate in the usual manner.

A blower 16 is connected to the interior of the furnace to create a forced draft and to supply the proper amount of air to effect 40 complete combustion of the fuel and to regulate the intensity of the fire in the furnace. This blower will be driven by an electric motor automatically controlled by temperature regulating devices appropriately located in the heated compartments or otherwise.

Positioned backwardly of the combustion chamber 14 there is a passageway 17 for the heated products of combustion extending rearwardly longitudinally of the boiler. At the rearward end of the boiler, there is a 45 baffle 18 in this passageway having a movable damper 19. The function of this baffle is to divert the heated gases forwardly through the lower tubes 7 to the forward end of the boiler into a compartment 20 whence they pass through the upper tubes 7

into the discharge flue 21. A control damper 22 is shown in the discharge flue and a clean out door 23 may be provided at the bottom of the passageway 17. The walls 24 surrounding the hot air passageway 17 may be constructed of suitable refractory insulating material, such, for example, as asbestos and fire clay.

For supplying the fuel to the combustion chamber 14, a fuel supply hopper 25 is positioned directly above the furnace and is shown as substantially surrounding the boiler 5. The walls of this fuel hopper may be constructed of any appropriate material as metal and may be lined with appropriate insulating or refractory material, especially in the vicinity of the combustion chamber. The fuel hopper has side and end walls 26 and a top wall 27 which may be removable or formed with a removable cover through which the fuel supply is introduced into the hopper. The bottom wall or floor of the fuel hopper is formed of downwardly and inwardly inclined plates 28. These plates preferably, as shown, incline downwardly and inwardly from the respective side walls terminating adjacent the grate 12 at the combustion chamber, thus providing inclined surfaces upon which the fuel rests so as to be caused to flow downwardly thereover by gravity toward the combustion chamber. This hopper construction thus provides oppositely disposed fuel passageways 29 inclining downwardly toward each other and meeting substantially in the combustion chamber above 100 the grates 12 and beneath the boiler 5. These passageways, as shown, may continue substantially for the entire length of the furnace and the combustion chamber thereof so that the coal is supplied uniformly throughout the length of said chamber.

Positioned above the fuel chutes or passageways 29 and adjacent thereto and to the boiler 5, and within the fuel hopper are fuel spreaders or controllers 30. As shown in the illustrative embodiment, there are preferably two of these spreaders, one at each side of the boiler. These spreaders are shown in the form of wing plates angular in shape, each being attached to and supported by the boiler 5. Each wing plate may be welded at its upper edge to the surface of the boiler or otherwise appropriately attached thereto as by means of an attaching flange 31 and attaching bolts 32 secured to the boiler. In some cases it is desirable to adjust the wing plates relative to the fuel passageways, and this may be done by providing holes 31' at different levels in the attaching flanges 31 for the reception of bolts, as clearly shown in Fig. 4.

Preferably each of the fuel spreaders 30 extends for the full length of the fuel chutes or passageways 29 along the boiler. The upper plate or flange 33 of each fuel spread-

er, as shown, preferably extends outwardly and downwardly from the boiler to a point adjacent to the upper end of the corresponding fuel chute, while the lower flange 34 is 5 turned abruptly inwardly extending downwardly for a short distance along the coal chute. This lower flange, however, may terminate, as shown, at some distance from the combustion chamber.

10. From the foregoing it will be seen that the spreaders or wing plates 30 function to correctly dispose or control the fuel at the top of the furnace so as to constantly maintain the fuel level in the furnace at the 15 proper height for most advantageous operation. Similarly, the spreaders maintain the space between the top of the burning fuel and the bottom of the boiler or crown plate at the desired degree for the best operation.

20. Coal which may be of small size is placed in the hopper through the top thereof which may be completely filled at one time. The hopper may vary in size but ordinarily it 25 will be of sufficient capacity to store coal sufficient to supply the furnace for several days. In this manner, it is only necessary to replenish the supply at relatively long periods and the capacity may be sufficient 30 for two to six days or even longer.

The flow of the coal to the combustion chamber from the supply is controlled by the arrangement above described including the inclined hopper bottoms and the wing 35 plates or spreaders 30. As the coal moves downwardly by gravity to and through the passageways or chutes 29, the spreaders will function to position the coal in the passageways, maintaining it at a constant level 40 which may be designated roughly by the wavy lines 35 in Figs. 1 and 2. It will thus be noticed that the fuel chutes are constantly maintained filled with coal up to these surfaces 35. It will also be noticed that the coal flows inwardly and downwardly in these 45 passageways, the two fuel streams moving toward each other in V formation and meeting substantially in the combustion chamber between the grate 12 and the boiler.

50. In this manner the combustion chamber is automatically supplied with fuel and the fire maintained, the blower 16 of course being operated as above suggested, to maintain the desired temperature. Thus, a vertical elongated ribbon or narrow zone of fire will be 55 constantly maintained extending longitudinally of the furnace and disposed between the grate and the boiler at the apex or meeting point of the V shaped chutes. The hot 60 gases of combustion of course pass upwardly impinging upon the boiler and pass along the passageways 17 and through the flues 7 to the chimney.

65. In this manner a most effective heating fire is constantly automatically maintained, it be-

ing only necessary to replenish the supply hopper at intervals and to maintain the operation of the blower and of the grate in the manner above mentioned. The improved apparatus is thus well adapted for very effective and economical operation.

70. Since certain changes may be made in the above construction and different embodiments of the invention could be made without departing from the scope thereof, it is intended that all matter contained in the above description or shown in the accompanying drawings shall be interpreted as illustrative and not in a limiting sense.

75. Having described my invention, what I claim as new and desire to secure by Letters Patent, is:

1. In a heating apparatus, in combination, a boiler, a combustion chamber having a grate, opposed fuel passageways leading to said combustion chamber and meeting at a point between the grate and the boiler, said fuel passageways being downwardly inclined toward each other for effecting gravity feed, a fuel storage chamber joining with and extending continuously and uninterruptedly upwardly from both of said fuel passageways and entirely enclosing the upper part of the boiler, and a fuel spreader positioned at each side of said boiler adjacent to the respective fuel passageway so as to control fuel flow to the combustion chamber, each of said fuel spreaders including a wing plate having an attaching and supporting lug by which it is directly connected to the boiler for vertical adjustment and extending longitudinally thereof adjacent to the respective fuel passageway so as to control and regulate the fuel level in the combustion chamber.

80. 2. In a heating apparatus, in combination, a boiler, a combustion chamber beneath said boiler, gravity feed fuel passageways downwardly inclining laterally in opposite directions and meeting in said combustion chamber, a fuel supply hopper extending continuously and uninterruptedly upwardly from said fuel passageways and joining therewith, and a longitudinally extending fuel spreader for each said fuel passageway positioned between said hopper and the respective passageway, each of said spreaders including an angle plate with the angle thereof projecting outwardly from the boiler at a point substantially between the fuel hopper and the respective passageway, one flange of each angle plate being connected to the adjacent side of the boiler and extending outwardly and downwardly therefrom, the other flange of each angle plate extending downwardly and inwardly from the first mentioned flange adjacent the upper part of the respective fuel passageway so as to control the fuel level in the combustion chamber.

85. 3. In a heating apparatus, in combination, a boiler, a combustion chamber having a

grate, opposed laterally disposed fuel passageways leading to said combustion chamber and meeting at a point between the grate and the boiler, said fuel passageways being 5 downwardly inclined toward each other for effecting gravity feed, a fuel storage chamber joining with and extending continuously and uninterruptedly upwardly from both of said fuel passageways and entirely enclosing 10 the upper part of the boiler, and a fuel spreader positioned at each side of said boiler adjacent to the respective fuel passageway at a point thereof substantially where the 15 said fuel chamber merges with the fuel passageway so as to control fuel flow to the combustion chamber, each of said fuel spreaders including a wing plate directly attached to the boiler and having an outwardly and downwardly inclined fuel guiding surface 20 adjacent to said fuel chamber.

4. In a heating apparatus, in combination, a boiler, a combustion chamber having a grate, opposed laterally disposed fuel passageways leading to said combustion chamber 25 and meeting at a point between the grate and the boiler, said fuel passageways being downwardly inclined toward each other for effecting gravity feed, a fuel storage chamber joining with and extending continuously 30 and uninterruptedly upwardly from both of said fuel passageways and entirely enclosing the upper part of the boiler, and a fuel spreader positioned at each side of said boiler adjacent to the respective fuel passageway 35 at a point thereof substantially where the said fuel chamber merges with the fuel passageway so as to control fuel flow to the combustion chamber, each of said fuel spreaders including a wing plate directly attached to the boiler 40 and having an outwardly and downwardly inclined fuel guiding surface adjacent to said fuel chamber, each of said wing plates having a supporting lug by means of which it is connected to the boiler 45 for vertical adjustment for varying the fuel flow through the respective fuel passageways.

In testimony whereof I affix my signature.
ROBERT S. RODIE.
